F. D. NEWBERRY.
TOOTH BRUSH HOLDER.
APPLICATION FILED DEC. 13, 1916.

1,234,199.

Patented July 24, 1917.

UNITED STATES PATENT OFFICE.

FRANKLIN D. NEWBERRY, OF JAMESTOWN, NEW YORK.

TOOTH-BRUSH HOLDER.

1,234,199.

Specification of Letters Patent. Patented July 24, 1917.

Application filed December 13, 1916. Serial No. 136,714.

To all whom it may concern:

Be it known that I, FRANKLIN D. NEWBERRY, a citizen of the United States, residing at Jamestown, in the county of 5 Chautauqua and State of New York, have invented certain new and useful Improvements in Tooth-Brush Holders, of which the following is a specification, reference being had to the accompanying drawings.

10 This invention relates to holders and has for its primary object to provide a simply constructed and serviceable holder for tooth brushes whereby a plurality of brushes may be supported or arranged and the brush 15 bristles completely housed and protected to obviate the possibility of contamination.

It is another important object of the invention to provide a holder for the above purpose, which is so constructed that any 20 one of the brushes may be very easily and quickly removed when it is desired to use the same, or replaced in the holder.

It is a further general object of my invention to provide a tooth brush holder 25 which is very simple and durable in its construction and is not only of great practical utility but also provides an ornamental fixture which may be produced at relatively small manufacturing cost.

30 With the above and other objects in view, my invention consists in the novel features of construction, combination and arrangement of parts to be hereinafter more fully described, claimed and illustrated in the 35 accompanying drawing, in which,

Figure 1 is a perspective view illustrating one embodiment of my invention;

Fig. 2 is a vertical section of the device;

40 Fig. 3 is a section taken on the line 3—3 of Fig. 2;

Fig. 4 is a vertical section showing a slightly modified construction; and

Fig. 5 is a similar view showing another modification.

45 Referring in detail to the drawing and more particularly to Figs. 1, 2 and 3 thereof, 5 designates the wall plate of a bracket which may be of any desired ornamental configuration, and to this plate an angularly 50 bent end of a metal tube 6 is centrally fixed in any approved manner. A second tube 7 is telescopically engaged in the vertically disposed portion of the tube 6, the tube 7 being fixed at one end centrally to a circular plate 8 which is provided on its outer

edge with the upstanding, annular flange 9. A plurality of equidistantly spaced, radially disposed slots 10 are formed in the plate 8 and extend through the flange 9 thereon, the inner ends of said slots being enlarged, 60 as at 11.

A rod 12 extends axially through the tube 7 and the vertical portion of the tube 6, and has a head 13 formed on its lower end which is permanently secured in any desired manner to the wall of the tube 6. Between the head 13 of the rod and the lower end of the tube 7, a coiled expansion spring 14 is disposed within the tube 6 and normally urges the tube 7 upwardly. The rod 12 extends some distance above the plate 8 and extends through a central opening in the upper end wall of the housing 15. This housing is preferably in the form of a glass or tumbler arranged in inverted position 75 upon the plate 8, the edge of the tumbler wall fitting within the flange 9 on said plate. Preferably, a flanged, metal bushing 16 is disposed in the opening in the end wall of the glass or tumbler in which the upper end 80 of the rod 12 is threaded. A cap nut 17 is also threaded upon the upper end of this rod, and the end of the rod swaged so as to retain the nut thereon.

Upon the flange 9 of the plate 8, a laterally projecting finger piece of any suitable form, shown at 18, is formed.

In the practical use of the device as above described, the plate 8 is moved downwardly in spaced relation to the lower edge of the 90 transparent housing 15 by a downward pressure upon the finger piece 18, and the shank portions of the tooth brushes at the inner ends of the bristles are moved inwardly into the inner ends of the slots 10 in said plate. 95 Upon the release of the plate 8, the coil spring 14, by its expansive action, forces said plate upwardly into tight engagement against the rim of the housing wall. Thus, the bristles of the tooth brushes will be 100 wholly disposed within said housing and protected so that dust cannot accumulate thereon or the same be otherwise contaminated. The plate 8 and the tube 7 may be readily rotated with respect to the housing 105 15 so that any desired brush will be disposed in convenient position for easy and quick removal when the holder plate is moved downwardly and spaced from the lower edge of the housing.

In Fig. 4 of the drawing, I have illustrated a slightly modified form of the device, wherein the plate 8' is fixed to the upper end of the vertical tube 6', the said plate being centrally provided with a relatively small opening to permit the vertically disposed rod 12' to move therethrough, said rod being fixed at its upper end to the top wall of the housing 15' in the manner above described. The lower end of this rod is provided with a head 13' vertically movable in the tube 6' and the spring 14' is interposed between this head and the fixed plate 8'. Thus, in this form of the device, it will be understood that the transparent housing is grasped and lifted from the upper surface of the plate 8', the spring 14' being thereby compressed so that it will act to return the housing to its normal position after the brush has been removed.

In Fig. 5, I have illustrated another slight modification of the form of the device shown in Fig. 2, wherein the tube 7' which is fixed to the holder plate, is engaged exteriorly upon the upper end of the relatively fixed bracket tube 6, and the upper end of the bracket tube is formed with an outwardly projecting bead 6' with which a similar bead on the lower end of the tubular standard 7' is adapted to engage to limit the upward movement of the latter standard. The spring 14a bears at its upper end against the under side of the holder plate. Thus, it will be understood that the device operates in identically the same manner as above described in connection with the preferred form of the invention.

From the foregoing description, taken in connection with the accompanying drawing, the construction, manner of operation and several advantages of the illustrated embodiments of the device will be clearly and fully understood. By means of my improved holder, the tooth brushes will be maintained in a thoroughly sanitary condition and a large number of the brushes may be arranged or supported in a comparatively small space. The housing 15, while preferably of glass in order that the brush heads may be visible, can likewise be constructed of metal or other opaque material if desired. This housing, as well as the plate 8, may be of various ornamental forms so that the device will present an attractive appearance as a bath-room fixture. It is also manifest that provision may be made in the plate 8 for any desired number of brushes and that the form, proportion and relative arrangements of the several parts may be greatly varied. I, therefore, reserve the privilege of resorting to all such legitimate changes in the practical development of the device which may be fairly em-

bodied therein within the spirit and scope of the invention as claimed.

Having thus fully described my invention, what I desire to claim and secure by Letters Patent is:—

1. A holder of the character described including a tubular bracket member, a supporting plate provided with means to support a plurality of brushes, said plate being movably mounted upon the bracket member, a housing inclosing the brushes in the normal position of said plate and preventing their removal therefrom, and a spring within the bracket member urging the supporting plate to its normal position with respect to the housing.

2. A holder of the character described including a housing open at one end, a plate to close the open end of the housing having means to support a plurality of brushes within the housing, and a spring yieldingly urging the plate into engagement with the housing, said plate being adapted for movement against the action of said spring to a position permitting of the removal of the brushes from the supporting plate.

3. A holder of the character described including a tubular bracket member, a relatively movable supporting plate mounted upon the bracket member and provided with means to removably support a plurality of brushes, a housing mounted upon the bracket member in fixed, spaced relation thereto, and a spring in the tubular bracket member urging said supporting plate in one direction and into engagement with the housing wall, whereby the articles on said plate are disposed within the housing and held against displacement from the plate.

4. A holder of the character described including a tubular bracket member, a standard telescopically engaged therein, a supporting plate fixed on said standard and provided with means to receive a plurality of brushes, a rod extending axially through the standard and into the tubular support and fixed at one of its ends to the latter, a housing fixed upon said rod, said plate and standard being rotatable with respect to the housing and the bracket, and a spring within the tubular bracket member co-acting with the standard to yieldingly hold the plate in engagement with the open end of the housing, whereby the articles on the plate are inclosed by the housing wall and held against removal from the plate.

In testimony whereof I hereunto affix my signature in the presence of two witnesses.

FRANKLIN D. NEWBERRY.

Witnesses:

M. C. LYDDANE,
M. R. WILSON.
